UNITED STATES PATENT OFFICE

PAUL GUGGENHEIM, OF PHILADELPHIA, PENNSYLVANIA, ASSIGNOR TO PHILADELPHIA METAL DRYING FORM COMPANY, OF PHILADELPHIA, PENNSYLVANIA, A CORPORATION OF DELAWARE

DRYING FORM

Application filed May 16, 1929. Serial No. 363,439.

This invention relates to a drying form and has particular reference to an adjustable foot construction for a hosiery drying form.

The primary object of the present invention is the provision of an automatically adjustable foot portion for a hosiery drying form which will maintain the foot of the hosiery in a properly extended condition during the heating and which will automatically 10 adjust itself to various sizes of hosiery.

A further object relates to the provision of a suitable arrangement of means for properly guiding and yieldingly urging outwardly the adjustable portion of the form in all positions 15 of use.

Another object relates to the provision of a device for limiting the outward movement of the toe extension of the form, which is automatically rendered operable upon assembly of the main portion of the form and the extension to thereafter limit outward movement of the extension.

Other objects relating to details of construction which result in a form of most desirable characteristics will be apparent from the following description read in conjunction with the accompanying drawings, in which:

Fig. 1 is a sectional view taken lengthwise 30 through the foot portion of the improved form;

Fig. 2 is a section on line 2—2 of Fig. 1; and Fig. 3 is a section on line 3—3 of Fig. 1.

The main portion of the drying form is indicated at 2. This portion is of the usual hollow type properly shaped to conform to and stretch the leg portions and heel of the hosiery during drying. In use, this portion is usually disposed vertically with the foot portion of the form extending upwardly to the side, as shown in Fig. 1. A suitable heating element 4 may be provided within the form and extends into the foot portion thereof. Instead of a heating device of this character, it will be obvious that any internal heating means may be provided.

The toe extension 6, formed hollow, as shown, telescopes within the foot portion of the form, the end of the foot portion being flanged inwardly, as indicated at 8, to closely

engage the toe extension to provide a substantially smooth article engaging surface at the junction in all of the various positions of adjustment of the toe extension.

While the above telescopic engagement 55 serves to support the extension to some extent, additional means are provided to accurately guide the extension as it is moved inwardly and outwardly of the main portion of the form. This means includes two tubes 60 12 which are supported by welding within apertures in a member 10, which is welded or otherwise secured to the walls of the main portion. The tubes extend to a position adjacent to the outer edge of the main portion 65 and are there supported by welding within the ends of a suitable spacer 14. Spacer 14 is spaced from the walls of the main portion of the form, so that the toe extension may be received therebetween. Tubes 16, secured 70 to the extension by means of flattened outer ends 18, telescope within tubes 12, as shown, thus forming guides insuring accurate inward and outward movement of the extension. These tubes are held in proper position by means of a spacer 19 to which they are secured. The circular base 20 of a guiding pin 22 is secured in the inner end of each of tubes 12, forming an abutment for each 75 spring 24 guided by the corresponding pin 80 22. These springs, by abutment between the bases 20 and the outer closed ends of tubes 16, serve to yieldingly urge the extension outwardly of the main portion. Such outward movement is limited by means of a 85 spring detent 26, the end of which, formed as indicated at 28, engages over the end of spacer 14. As illustrated, the end 28 slopes inwardly and upwardly, while it is provided with an angular portion adapted to engage 90 the end of the spacer. By this arrangement, when the extension and main portion are assembled by telescoping the tubes and pressing the extension inwardly, the upturned end 28 rides over spacer 14 and then snaps behind the same, so as to thereafter limit outward movement of the extension relatively 95 to the main portion of the form.

Springs 24 are preferably of light construction so as to permit ready yielding of 100

the toe extension inwardly. Normally the toe extension may move to a position limited by the detent 26 such that the total length of the foot portion is sufficient to accommodate 5 the largest size hosiery which it is desired to dry on the form. If a smaller size of hosiery is placed on the form, the extension will yield inwardly to accommodate this hosiery, the 10 light springs 24 serving to maintain the foot portion of the hosiery in stretched condition. The hosiery is maintained on the form against the resiliency of springs 24 by engagement of the heel portion over the heel 15 portion of the form. The form, due to the resiliency of the springs, then automatically takes care of any shrinking by the inward movement of extension 6.

What I claim and desire to protect by Letters Patent is:

1. A drying form comprising a main portion, an extension telescopically adjustable relatively to the main portion, and means automatically rendered operable upon assembly of the main portion and extension to thereafter limit outward movement of the extension relatively to the main portion, said extension being yieldingly urged outwardly to a position defined by the limiting means and being movable inwardly independently 25 of the limiting means.

2. A drying form comprising a main portion and an extension telescopically adjustable relatively to the main portion, the outer surfaces of the main portion and extension 30 overlapping and being formed to produce a substantially smooth article engaging surface at their junction in various positions of adjustment, telescoping tubes carried by the main portion and extension respectively, and 35 a spring within the tubes serving to urge the extension outwardly of the main portion.

3. A drying form comprising a main portion and an extension telescopically adjustable relatively to the main portion, the outer 40 surfaces of the main portion and extension overlapping and being formed to produce a substantially smooth article engaging surface at their junction in various positions of adjustment, telescoping tubes carried by the 45 main portion and extension respectively, a spring within the tubes serving to urge the extension outwardly of the main portion, and means limiting the outward movement of the extension.

4. A drying form comprising a main portion and an extension telescopically adjustable relatively to the main portion, the outer surfaces of the main portion and extension 50 overlapping and being formed to produce a substantially smooth article engaging surface at their junction in various positions of adjustment, telescoping tubes carried by the main portion and extension respectively, a 55 spring within the tubes serving to urge the extension outwardly of the main portion, and

means limiting the outward movement of the extension, said means including a spring detent and a stop carried by the main portion and extension and automatically engageable upon initial assembly of the main portion and extension. 70

5. A drying form comprising a main portion and an extension telescopically adjustable relatively to the main portion, the outer surfaces of the main portion and extension overlapping and being formed to produce a substantially smooth article engaging surface at their junction in various positions of adjustment, a heating element in the main portion, a tube carried by the main portion adjacent the heating element, a tube carried by the extension and telescoping with the first mentioned tube, and a spring serving to urge the extension outwardly of the main portion. 75

6. A drying form comprising a main portion and an extension telescopically adjustable relatively to the main portion, the outer surfaces of the main portion and extension overlapping and being formed to produce a substantially smooth article engaging surface at their junction in various positions of adjustment, a heating element in the main portion, a tube carried by the main portion adjacent the heating element, a tube carried by the extension and telescoping with the first mentioned tube, and a spring serving to urge the extension outwardly of the main portion, and means limiting the outward movement of the extension. 90

In testimony of which invention, I have hereunto set my hand, at Philadelphia, Pennsylvania, on this 1st day of May, 1929.

PAUL GUGGENHEIM.
